UNITED STATES PATENT OFFICE

DALLAS D. WERTZBERGER, OF TULSA, OKLAHOMA

TOP CASTING AND DERRICK CONSTRUCTION

Application filed June 2, 1928. Serial No. 282,327.

This invention relates to improvements to top castings and derrick constructions, and more particularly to top castings highly desirable for use on derricks to support an upper fabricated unit or section thereon, in an improved manner of construction, although devices of the type described herein embodying the present invention may be used on any desirable fabricated structure 10 as well as in other places as will be apparent to one skilled in the art.

At the outset it is to be distinctly understood that although the present invention is disclosed as associated with a combination 15 of pipe and steel oil derrick, the same is readily adaptable, by very slight changes in the construction thereof, for use in practically any kind of fabricated structure without departing from the spirit of the 20 present invention.

In the oil fields it has been found desirable to erect derricks as economically as possible and with as great rapidity as possible. Obviously, derricks may be put up in advance of their use to a greater extent if only 25 a tentative scheme of the under mechanism is used, i. e., if just a preliminary and not a final plan for the disposition of the walking beam and bull wheel is used. Then 30 when the lower mechanism is installed, certain of the derrick structures may be altered to accommodate the final plan or layout of ground mechanism. In other instances, it may be found desirable and advantageous 35 to change the scheme of the ground mechanism, and obviously, a derrick which could be easily adjustable to accommodate such changes would be most efficient.

In the past, derricks have usually been 40 constructed with the location of all ground structure predetermined and definitely decided upon. The derricks including the crown blocks and upper mechanism were constructed with the definite layout of the 45 ground mechanism in mind, and with these formerly known derricks, to change the crown blocks and other upper mechanism, it was necessary to practically dismantle and rebuild the same. Moreover, these former- 50 ly known derricks were, in most instances,

complicated to an objectionable extent and necessitated an undesirable amount of time and labor in their construction. Further, in the event a crow's nest was mounted thereon, which is highly desirable in modern derricks, there was not sufficient room in the 55 crow's nest to repair, adjust, or give adequate attention to the upper mechanism.

The present invention is designed to overcome the above noted defects and objections in the provision of a derrick in which the upper structure is exceedingly simple, and in which certain elements are provided to each perform the work which was heretofore done by a plurality of elements involving a complicated structure.

The present invention also seeks to provide a derrick equipped with means for mounting a water table so that the water table may be mounted or removed as an 70 entire unit, and not built up piece by piece in the construction of the derrick.

A further object of the present invention is to provide simple means for mounting a water table or upper section in such a manner that the same may be removed, rotated a predetermined angle and easily remounted in its new position.

Another object of the present invention is to provide means for mounting a water 75 table or upper section on a fabricated structure in such a manner that the aforesaid water table or section may be rotatably adjusted to any desired angle without dismantling any part of the fabricated structure proper, thereby enabling the mounting of a crown block or the like in any desirable position regardless of the original position 80 of ground mechanism relative to the water table or crown block.

A still further object of the present invention is to provide a derrick equipped with a crow's nest and a crown block mounted in such a manner that ample space is provided for attending or adjusting the 85 crown block from the crow's nest.

A still further object of the present invention is to provide ample and efficient means in a fabricated structure for supporting a fabricated unit or section which 100

is mountable as a unit or piece by piece and removable or adjustable in the same manner.

A still further object of the present invention is to provide a simple casting or otherwise formed element adapted to engage a portion of the fabricated structure and to support a portion of the aforesaid structure in such a manner that the position of the supported portion is variable at will.

10 While some of the more salient features, characteristics, and advantages, of a device embodying the present invention have been above pointed out, others will become apparent from the following disclosures.

15 The invention includes these and other features of construction and combinations of parts hereinafter described, and shown in a preferred form in the drawings, as more particularly indicated by the claims.

20 On the drawings:

Figure 1 is a fragmentary view in elevation of a derrick equipped with an upper structure mounted on means embodying principles of the present invention.

25 Figure 2 is an enlarged fragmentary view in elevation of the upper portion of Figure 1.

Figure 3 is a plan sectional view taken substantially as indicated by line III—III 30 of Figure 2.

Figure 4 is a plan view of one of the supporting elements embodying principles of the present invention.

35 Figure 5 is a bottom plan view of the element shown in Figure 4.

Figure 6 is an enlarged fragmentary sectional view taken substantially along line VI—VI of Figure 3.

40 Figure 7 is a fragmentary plan sectional view taken substantially along line VII—VII of Figure 6.

As shown in the drawings:

The structure selected to adequately disclose the illustrated embodiment of the present invention includes foundation means generally indicated by reference numeral 1, which may be of any desired type or of the type set forth in my copending application for foot castings for derricks and 45 method of using the same, of even filing date, Serial No. 282,328, which has matured into Patent No. 1,781,889, November 18, 1930, upon which foundations is mounted a derrick generally indicated by reference numeral 2 and which includes a plurality of legs 3, girts 4, and braces 5. The legs 3 are preferably in the form of pipes for facilitating erection. Adjacent the upper portion of the derrick 2, a set of the girts 4 50 together with angular securing means effectively provide a mounting base 6 for crow's nest supports 7 which, together with other means to be hereinafter described, effectively support a crow's nest 8.

60 Novel means are provided in the present

instance for supporting the inner portion of the crow's nest 8 as well as supporting a crown block support or water table. These means preferably embody the form of a casting, shown more clearly in Figures 4 70 and 5, which is engageable with one of the legs 3 of the derrick, there being as many castings employed as the derrick has legs. Each of the castings comprises a plate 9 from which an outwardly inclined tubular 75 portion 10 depends and which is slidable over the upper extremity of one of the legs 3 of the derrick, to which it is secured by means of a bolt 11 passing through the tubular portion 10 and leg 3. Projecting 80 normally from the tubular portion 10 and substantially at right angles to each other, are a pair of wings 12 which are provided with elongated apertures to accommodate bolts or rivets 13, or any desirable securing 85 means, by which girts 4 and braces 5 are attached to the wings, as seen more clearly in Figure 6. Since both the legs 3 and tubular portion 10 have the same inward slant the plate 9 will be substantially horizontal. The plate 9 is provided with a plurality of apertures, elongated to permit adjustments which will be herein designated as groups 14, 15 and 16.

When a casting is mounted on the top of 95 each of the derrick legs 3, there will be, in this instance, four substantially horizontal plates 9 disposed at the upper corners of the derrick proper. These plates afford ready and efficient means for the mounting thereon of a water table or crown block support which, in this instance, comprises a pair of parallel crown block supports 17—17 preferably in the form of I-beams which are connected adjacent their extremities by 100 transverse crown block support headers 18—18 which are preferably connected to the supports 17—17 by angle irons 19—19 riveted both to the headers 18—18 and supports 17—17, as seen more clearly in Figure 7.

Mounted on the crown block supports 17—17 adjacent the mid-portions thereof is a crown block which, in this instance, is only diagrammatically shown, and comprises a 115 pair of transverse pulley supports 20—20 upon which a crown pulley 21 is mounted.

From the foregoing it will be apparent that the entire water table or crown block support is preferably mounted on the derrick in one complete single unit and not built up thereupon as has been the customary practice. When the water table is disposed on the plates 9, as shown in Figure 3, the supports 17—17 are bolted to the plates 9 by bolts 14a passing through the apertures 14 in the plates. The corner apertures 16 in the plates 9 accommodate bolts 16a which secure crow's nest floor supports 22 to the plates. The remainder of the crow's 125

nest floor supports are secured to the top girts 4 of the derrick, which lie beneath the supports 17-17 and headers 18-18 of the crown block. In this instance, the apertures 15 in the plates are unused and left open.

Now assuming it is desired to change the position of the crown block, for instance, ninety degrees, so that the crown 10 pulley will be disposed transversely to the position shown in Figure 3, it is simply necessary to remove the bolts 14a from the the crown block supports 17-17, lift the entire water table, the crown block being 15 carried therewith, rotate it ninety degrees and again bolt it to the plates 9, utilizing the apertures 15, in this instance, and leaving the apertures 14 open. Obviously, in many instances, the crown block alone may 20 be adjusted to a new position without moving the water table. To aid in manipulating the crown block or water table or both, a gin pole structure is provided which includes a pair of upright gin pole supports 23 25 which are secured adjacent their lower extremities to the mounting base 6 in any desired manner and also to the top girts 4 as indicated at 24 in Figure 3. The gin pole supports are projected well above the crow's 30 nest and crown block and are joined at their upper extremities by a gin pole beam 25, to which any desired tackle may be secured for the proper handling of the crown block.

It should be noted, with the structure set 35 forth herein ample room is left at the crow's nest to facilitate adjustments of, or attention to, the crown block or water table which are both disposed substantially at the same level as the floor of the crow's nest. 40 It will also be noted that if, for any reason, it is desired to move or shift the position of the crow's nest as an entirety, it is simply necessary to release the floor supports thereof from the plates 9 and top girts 4 and release the crow's nest supports 7 from the mounting base 6, when the entire crow's 45 nest may be handled at will.

From the foregoing, it will be apparent that I have provided novel top castings or 50 supporting elements for derricks or any desirable fabricated structure, which are each engageable with girts, braces and a derrick leg, and adapted to support a water table or any desirable fabricated unit, to thereby 55 provide a rigid and durable structure. Obviously, the positions and locations of the castings may be varied as found convenient to support any desired portion of the fabricated structure. Moreover, the castings as 60 described herein are means to enable a novel top structure to be erected on a derrick affording ample room for workers and permitting the ready adjustment of the crown block to any desirable position. Further, 65 the castings, water table, and associated

structure, described herein, may be economically manufactured, assembled and dismantled.

It is to be clearly understood, however, that though the supporting elements are described as castings they may be formed in other ways and manners without departing from the spirit of this invention. It should also be understood that while the terms derrick, girts, braces, and water table, are used herein and in the appended claims, the supporting elements may be used with various cross-rods and bracing means in various types of fabricated structures, within the scope of this invention.

I am aware that many changes may be made and numerous details of construction may be varied through a wide range without departing from the principles of this invention and I, therefore, do not purpose 85 limiting the patent granted hereon otherwise than necessitated by the prior art.

I claim as my invention:

1. In combination, a derrick superstructure, a top section thereon, and means associated with said top section for supporting a crown block in positions at right angles to each other.

2. In combination, a fabricated structure including a plurality of legs, a top section on said structure including a crow's nest, unitary means connected to each of said legs and engageable with floor supports of said crow's nest, and crown block supports supported by said means at substantially the 100 level of the floor supports of said crow's nest.

3. In combination, a derrick including a plurality of legs, girts and braces to rigidify said derrick, a crow's nest on said derrick, a crown block support on said derrick, and integral means at each corner of said derrick engageable at once with one of said legs, a plurality of said girts and braces, floor supports for said crow's nest, and with said 110 crown block support.

4. As an article of manufacture, a supporting element for an upper portion of a fabricated structure, said element including a plate provided with a pair of sets of elongated apertures, one set for accommodating securing means for said upper portion when in one position, and the other set for accommodating securing means for said upper portion when in another position, and means on said plate for engagement with a main member of said structure.

5. As an article of manufacture, an element for supporting an upper portion of a fabricated structure, said element including a plate having a plurality of sets of apertures therein, each set accommodating securing means for said upper portion for an individual position of the latter, an outwardly inclined portion depending from said plate 130

for engagement with a leg of said structure, means for securing said portion to said leg, and angularly related wings provided with apertures to receive securing means on said depending portion, said wings being each engageable with bracing means of said structure extending in a plurality of directions.

6. In combination, a derrick superstructure, a top section thereon and crown block supporting means associated with said top section including means for enabling the crown block to be secured thereto in one position and means for enabling the crown block to be secured thereto in another position at right angles to the first position.

10 16. In testimony whereof I have hereunto subscribed my name at Tulsa, Tulsa County, Oklahoma.

DALLAS D. WERTZBERGER.
